UNITED STATES PATENT OFFICE.

WALTER H. WATTS, OF LOS ANGELES, CALIFORNIA.

ICE-CREAM SERVICE CABINET.

Application filed March 18, 1926. Serial No. 95,700.

This invention relates to ice cream service cabinets, and is particularly adapted to serve as an ice box for the reception of a multiplicity of ice cream bricks and to provide means whereby measured slices of the ice cream may be served from a brick and served to the customer without exposing the bulk of the ice cream to the warm temperature of the room in which the cabinet is installed.

The above and other objects of the invention will become apparent from the following description, and by reference to the accompanying drawings, in which:

15 Figure 1 is a front view of a cabinet embodying the invention.

Figure 2 is a vertical section of the same taken on line 2—2 of Figure 1.

20 Figure 3 is a transverse section, taken on line 3—3 of Figure 1.

Figure 4 is an enlarged fragmental section of the lower portion of Figure 2.

Figure 5 is an enlarged fragmental section of part of Figure 3.

25 Figure 6 is an enlarged view of the top of the ice cream brick container.

Figure 7 is an enlarged section through the lower portion of the ice cream brick container taken on line 7—7 of Figure 4.

30 In carrying out the invention, 10 represents a cabinet of suitable dimensions, having an inner metal lining 11. The cabinet is provided with a top removable cover 12, a front door 13 which is hinged at 14 in order that it may swing downwardly and outwardly, and a small door 15 hinged at 16 adapted to be opened when it is desired to remove a slice of the ice cream, and also when opened to serve as a shelf, it having 35 formed thereon a stop 17 which rests against the cabinet and forms a support therefor.

The lining 11 is offset rearwardly at the front of the doors 13 and 15 to form a pocket 18, for the reception of a plurality of ice cream containers 19 which are supported on the inner face of the door 13. Ice is placed in the chamber 20 of the cabinet and contacts with the walls on three sides and at the top and bottom of the pocket 18, thus keeping the contents of the container 19 frozen at all times.

45 The containers 19 are preferably formed of rectangular metallic tubes and are provided on their inner surfaces with vertically disposed ribs 21 which form only a slight

contact with the ice cream bricks 22 which are stacked one upon the other in the containers, and thereby enable the bricks to slide freely therein, and not freeze or stick to its surface. The containers 19 are guided 60 in ways or tracks 23 which are secured to the door 13 and are held from downward movement by means of a ledge 24 formed at the top of each container and adapted to contact with the top surfaces of tracks or 65 ways 23.

The lower end of each container is provided with two sets of slide ways, the upper slide way 24 being adapted for the guidance of a slidable ice cream cutting blade 25, and the lower slide way 26 being adapted for the guidance of the slidably mounted ice cream tray 27, said tray being provided with a suitable handle 28. The cutting blade 25 is provided with a hinged handle 29 in 70 order that it may be properly manipulated to perform its function, and which may be folded inwardly and out of sight when the cabinet door 15 is closed.

75 Figure 6 is an enlarged view of the top of the ice cream brick container.

Ice is placed in the chamber 20 through the top door 12, the door 13 is swung open and the ice cream bricks are placed in the containers 19, a different flavor in each container if desired, the bricks falling by gravity until the bottom one contacts with 80 the blade 25.

85 When it is desired to serve an order of the ice cream, the server opens the door 15, pulls outwardly on the handle 29, thereby pulling out the slide blade 25, the ice cream brick then falls and contacts with the bottom of the tray 27; the blade 25 is then pushed rearwardly, thus severing a measured portion from the brick; the tray 27 is then removed from the container and the measured portion of the ice cream therein is 90 dropped upon the serving plate.

95 Having thus described my invention what I claim is:

1. An ice cream service cabinet, comprising a cabinet, a door for said cabinet, an ice cream container mounted on said door, and means associated with said container for severing portions from the ice cream held in said container.

100 105 110 115

2. An ice cream service cabinet, comprising a cabinet having means whereby the interior of the same may be kept cool, a door for said cabinet, an ice cream container removably mounted on said door, a severing

blade associated with said container, and a measuring tray associated with said container.

3. An ice cream service cabinet, comprising a cabinet, a door hinged at its bottom to said cabinet, guide ways secured on the inner surface of said cabinet, a container mounted in said guideways, a severing blade slidably mounted on said container, and a measuring tray slidably mounted on said container.

4. An ice cream service cabinet, comprising a cabinet, a door for said cabinet, an ice cream container mounted on said door, said container being provided with internal slight contacting surfaces, and means asso-

ciated with said container for severing portions from the ice cream held in said container.

5. An ice cream service cabinet, comprising a cabinet, a door hinged at its bottom to said cabinet, a container removably secured to said door, a severing blade slidably mounted on said container, a measuring tray slidably mounted on said container, and a second door hinged on said cabinet arranged adjacent the severing blade and measuring tray. 20 25

In testimony whereof I hereunto affix my signature.

WALTER H. WATTS.
